UNITED STATES PATENT OFFICE.

ADELBERT A. THOMAS, OF BOSTON, MASSACHUSETTS, ASSIGNEE TO FARRINGTON MANUFACTURING COMPANY, OF BOSTON, MASSACHUSETTS, A CORPORATION OF MAINE.

BOX.

1,092,961.

Specification of Letters Patent. Patented Apr. 14, 1914.

Application filed March 12, 1910. Serial No. 548,940.

To all whom it may concern:

Be it known that I, ADELBERT A. THOMAS, a citizen of the United States, and residing at the city of Boston, in the county of Suffolk, and Commonwealth of Massachusetts, have invented certain new and useful Improvements in Boxes, of which the following is a specification.

This invention relates especially to the construction of small boxes or receivers for jewelry and other small objects, and has for its object the effecting of the improvements in details hereinafter set forth.

Referring to the drawings forming part of this specification, Figure 1 is a vertical section of a box made in accordance with my invention. Fig. 2 is a perspective view illustrating the means whereby the members composing the sides are fastened together, and also whereby the bottom is secured to the sides; the top being affixed to the members composing the cover in the same manner. Fig. 3 is a perspective view of said bottom, but is equally illustrative of the top. Fig. 4 is a perspective view of one of the devices for fastening said members together.

In constructing this box, the four members composing the sides of the lower section of the box consist of the wooden strips 1 and 2;—1 designating the ends and 2 the sides,—are preferably placed in a suitable holding means with their ends closely contacting, and such ends fastened strongly together, as by the devices illustrated in Fig. 4. These fastening devices consist each of a sheet metal angle 3 having integral fingers 4 at the top and bottom edges; eight such fingers being preferred for each angle-piece. These angle-pieces are placed within the corners of the members 1 and 2, and said fingers bent tightly over the edges of the same, as in Fig. 2. These members 1 and 2 may then be removed from the holding means aforesaid, and a strip of fabric, paper or other covering material 5 (Fig. 1) pasted about the outer periphery of the box; such covering preferably inclosing the upper and lower edges of the latter and coming over more or less upon the inner surface of the box-members. The sheet metal fastening devices 3 being very thin, and their fingers forced slightly into the soft wood composing the box-members, said fastening de-

vices are practically invisible after said covering has been pasted upon the box. It 55 should be noted that this covering is applied to the box-members 1 and 2 before the bottom is affixed thereto, and the work of applying the covering being all straight forward, that is, all "straight work," it is very readily 60 and economically done. A rectangular piece of sheet metal 7 slightly larger than the exterior of said box-members, is now formed and a number of spurs 8 struck up therein, the latter being located to fit up tightly 65 within the box members. A similar covering 9 is then pasted to the under face of this bottom, and the edges of such covering brought up and over the outer edges of the bottom into substantial contact with said 70 spurs. This is indicated in Fig. 1. This covered bottom 7 is then applied to the box-members 1, 2, and said spurs terminally bent outward into the material composing said members, as in Fig. 2, thereby strongly 75 fastening said sides and bottom together.

The side members composing the cover are put together in precisely the same way, and the top 10 formed with spurs 8 and fixed upon said members 11, as just described; the 80 only difference consisting in preferably stamping said top into a slightly bellying form, as indicated in Fig. 1, the object being that of improving its appearance. When thus having the top convexed, it is well to 85 have the side-members of the cover not quite so high as the members 1, 2; this also being for the purpose of making the box more attractive in appearance. The box may now be provided with hinges and locks of usual 90 types, and giving linings 14 and 15.

For smaller and cheaper jewelry boxes, the sides may be glued together and the fastening devices 3 dispensed with; the covering which is stretched about said members serving to hold them together with considerable strength. It should be made clear that in thus covering said sides, a strip of the fabric or other material is first pasted to one part of the outer surface of the box, 100 as at A in Fig. 2, and then passed therefrom about one corner, as B, and thence along the end of the box to the next corner; then along the following side 2, and so on around to the place of beginning. This is evidently 105 a simple task, but a method which securely

binds the box members to each other as just described.

What I claim as my invention and for which I desire Letters Patent, is as follows,
5 to wit;—

1. A case for jewelry and the like comprising wooden side-members fastened together at their ends, and a sheet metal plate corresponding in outline to the outer periphery of said side-members and extending slightly beyond the same, said plate having spurs struck up from it within said side-members, each spur having its sharp end bent at right angles to the body thereof and forced into the substance composing the side-members and such body being brought flat against the inner surface of the side-member thereat.
2. A case for jewelry and the like comprising wooden side-members fastened together at their ends, a covering applied to the outer periphery thereof and over the

edges of the same, a sheet metal plate corresponding in outline to the said periphery and extending slightly beyond the same, a 25 covering applied to the outer face of the plate and brought over upon the inner surface for a substantial distance and between said plate and upper edges of said side-members, and spurs for fastening said plate 30 to the side-members, said spurs being struck up from the plate within the side members and each having its sharp end bent at right angles to the body thereof and forced into the side-members, whereby said plate and 35 side-members can be covered separately and then fastened together.

In testimony that I claim the foregoing invention, I have hereunto set my hand this 8th day of March, 1910.

ADELBERT A. THOMAS.
